UNITED STATES PATENT OFFICE.

WILLIAM H. CARR AND JOHN G. WOLF, OF NEW YORK, N. Y.

PLACKET-PROTECTOR AND SKIRT-SUPPORTER.

SPECIFICATION forming part of Letters Patent No. 620,885, dated March 14, 1899.

Application filed May 19, 1898. Serial No. 681,137. (No model.)

To all whom it may concern:

Be it known that we, WILLIAM H. CARR and JOHN GEORGE WOLF, citizens of the United States, residing at New York, in the county 5 and State of New York, have invented new and useful Improvements in Placket-Protectors and Skirt-Supporters, of which the following is a specification.

By means of this device a dress or skirt may 10 be held closed and in place relatively to the waist or body portion of the garment; and the invention consists in the novel features of construction set forth in the following specification and claim, and illustrated in the annexed drawings, in which—

Figure 1 is a rear elevation of the placket-holder. Fig. 2 is a side elevation of Fig. 1, partly in section. Fig. 3 is a plan view of Fig. 1, partly in section. Fig. 4 shows the 15 placket-holder open. Figs. 5 and 6 show a modification.

The members 1 and 2 are shown pivoted or jointed together at their lower ends at 3. The two members can be suitably spaced, as by a 20 washer 4, Fig. 2, at the pivot or joint 3. The inner or forward member 2 is formed or provided with a keeper 5, having a slot or eye 6, adapted for the reception of a stud or lock 7 on the other member. When the stud 7 is 25 passed or secured in slot 6, the holder is closed. The keeper 5 is shown hook-shaped or projecting forward from the upper part or end of member 2. Such keeper or its forwardly-projecting part has a stud 8. The belt or 30 waistband 9 is shown adapted for the engagement of stud 8. A keyhole-slot 10 11 in said belt or in a plate or attachment 12, secured to the belt, enables the stud 8 to be readily engaged to or freed from the belt.

40 The belt or band 9 being secured to or clasped about the waist and the placket-closer 1 2 being on a dress or skirt, the skirt can be suitably closed and held up to the waist. The

waistband of the skirt being clasped over or about belt 9 conceals the latter. At the same 45 time the members 1 and 2 can be readily opened or their interlocking engagement at 7 freed and also disconnected from the belt or waistband 9.

A hook 14 is shown detachably secured in 50 a suitable way to the upper part of the placket-protector; but this hook can be omitted. It is, however, of service—as, for example, to engage an outer or exposed belt. The slot, as seen at 11 in Figs. 5 and 6, can have a depression or seat 15, which when stud 8 is placed therein will prevent lateral movement or accidental sliding or derangement of the placket-closer. In Fig. 5 the slot 11 is shown at the right cut clear through the projecting 55 portion of plate 12, so that the stud 8 can be slid in and out at the right-hand end of slot 11.

What we claim as new, and desire to secure by Letters Patent, is—

A placket-protector and skirt-supporter, 65 comprising two members pivotally connected together at their lower ends, one of said members being provided at its upper end with an inwardly-projecting stud, and a slot formed laterally in the edge of the upper portion of 70 the other member and adapted to receive and retain said stud, the upper end of said last-mentioned member being bent downward to form a hook and provided with a headed stud, in combination with a belt having a horizontal 75 keyhole-slot arranged to engage said headed stud, substantially as described.

In testimony whereof we have hereunto set our hands in the presence of two subscribing witnesses.

WM. H. CARR.
J. G. WOLF.
